2 Sheets-Sheet 2

UNITED STATES PATENT OFFICE.

FERDINAND D. MAGUOLO, OF ST. LOUIS, MISSOURI.

SHOWCASE REFRIGERATOR.

Application filed April 9, 1923. Serial No. 630,842.

To all whom it may concern:

Be it known that I, FERDINAND D. MAGUOLO, a citizen of the United States, residing at St. Louis, in the State of Missouri, have invented certain new and useful Improvements in Showcase Refrigerators, of which the following is a specification containing a full, clear, and exact description, reference being had to the accompanying drawings, 10 forming a part hereof.

My invention consists in the novel disclosure of means for refrigeration; as herein-after particularly described and distinctly claimed.

15 The object of my invention is to improve the construction and increase the efficiency of show-case or counter refrigerators.

In the drawings,

20 Fig. 1 is a front-elevation of one form of my invention, partly in section.

Fig. 2 is a transverse vertical section of the same, taken on the line 2—2 of Fig. 1.

Fig. 3 is a top plan-view of same, partly in section, parts being cut and broken away 25 to more clearly show the underlying constructions.

Fig. 4 is a detail perspective view of one of my improved freezing (or air-cooling) tubes, and the means for supporting it in 30 the ice-container of the refrigerating-compartment, and

Fig. 5 is an enlarged detail-view of the sectioned parts shown at the upper right-hand corner of the ice-container of Fig. 1, 35 to more clearly exhibit the construction of the air-inlet in the upper portion of said ice-container, as well as that of the inner metal cover of the latter.

The show-case compartment.

40 In the present illustration I have shown a double-ended show-case 1, having a refrigerating-compartment at both of its ends; but it will be readily apparent that a single refrigerating-compartment at one end only 45 of said show-case may be used, if so desired; and likewise, the invention may be applied to other well-known styles of refrigerators.

The numeral 1 designates a show-case

compartment, in which the articles to be 50 refrigerated are to be placed, displayed, and supported.

Said compartment 1 is, in the present illustration, provided with a white-tile floor 2, but of course any other material (such as 55 sheet-metal) can be used for the floor, in place of said white-tiling. Supporting-shelves or racks 3 are provided.

Transparent panels 4 in the front, top, and doors of said show-case compartment 60 are provided with a plurality of two or more panes of glass separated by a dead-air space, to act as efficient insulation without interfering with the view of the articles on display in said compartment.

Access to the lower part of said show-case compartment 1 may be had by opening the doors 5, which are located in the rear of the compartment, near the floor thereof; and these doors are (in the present case) provided with suitable insulation, in the form of a plurality of layers of insulating material separated by a dead-air space. If preferred, said doors 5 may also be made with transparent panels 4 of the same construction as 70 that above described for the front, top, and display-doors of the show-case compartment, instead of having said layers of opaque insulating material.

A suitable insulating bottom wall is provided beneath the said show-case compartment 1, and in the present form the said insulating bottom wall has two (or a larger number of) parallel sections of insulating-material, separated by a dead-air space 7, 85 which makes the wall lighter in weight and cost, and at the same time renders it very highly efficient.

The refrigerating-compartments.

At both ends, or (if preferred) at one end only, of the said show-case compartment 1, is a refrigerating-compartment 6 that is open to said show-case compartment at all times, so there will be a continuous circulation of air in the compartments.

The said show-case floor 2 is extended into, and forms the floor of said refrigerat-

ing-compartments 6, and the bottom insulating-wall (having the dead-air space 7) is also extended beneath said refrigerating-compartments.

5 Insulating-walls, having the dead-air spaces 7, are also applied to the top and three outer vertical walls of the said refrigerating-compartments 6.

Access to the said refrigerating-compartments may be readily had by opening the doors 8 in the top thereof; said doors forming a part of the dead-air space insulating-wall of said compartments.

An ice-container 9 is located in each of the said refrigerating-compartments 6, and is placed therein and may be removed through the door-openings of said doors 8, which open directly above the tops of said ice-containers, as herein shown. Fig. 1.

20 Each of said ice-containers 9 is preferably made rectangular in shape, of suitable sheet-metal, and is suspended or otherwise supported in its refrigerating-compartment 6, in such a manner that there will be a free space for the circulation of air between the top, bottom and sides thereof and the adjacent walls of the said refrigerating-compartments, as well as upon the interior of said ice-containers.

30 In the present construction, each of said ice-containers 9 has an outwardly-turned marginal-flange 10 at its upper end, resting upon a series of horizontal supporting-bars 11, which are fixed at the top of the said refrigerating-compartments 6, so that in removing said ice-containers, for cleansing or repairs, it will only be necessary to open the said top-doors 7, and lift said ice-containers out through the openings of said doors.

40 A shallow sheet-metal ice-pan 12 is placed above each of said ice-containers 9, so that cracked-ice and salt or other refrigerant, may be packed in said pan, to cool the upper portions of said ice-containers, after the latter have been packed with refrigerant. Fig. 5.

The said ice-pans 12 are suspended in the upper portion of the ice-containers 9 by means of a horizontal marginal-flange 14 on the upper edge of said pans, resting upon the said marginal-flange 10 of the said ice-containers.

Formed in the bottom of the ice-pans 12 is a filling-opening 15, which is occupied by the vertical-flange 16 of a detachable lid 17. A suitable handle 18 is arranged upon the upper surface of said lid, for convenience in handling the latter.

When said lid 17 is in a closed position, it is supported by an inwardly-extending horizontal flange 19, that is integral with or attached to the lower ends or edges of the vertical walls of its ice-pan 12. A common gasket or weather-strip 20, having a soft or yielding strip of material, such as rubber 21,

is attached to one of the opposing surfaces to be made air-tight, by means of rivets 22 or other fastenings. Fig. 5.

A horizontal air-duct or air-passage entirely surrounds the upper portion of each of the ice-containers 9, to receive air and vapors from the upper portion of the said show-case compartment 1, and distribute and discharge same at various points around (and within) said ice-containers. 23 designates said air-duct.

One way of providing such horizontal air-ducts or passages is as follows:—

Depending from the inner edge of said lid-supporting horizontal flange 19 of each ice-pan 12, is a vertical inner-wall of said air-duct 23, which is preferably formed integral with said flange, and carries at its lower edge an upwardly-inclined bottom-plate 24 that is provided with numerous 85 perforations 25.

A vertical rim or guide-flange 26 is formed integral with and depends from the outer edge of the said inclined-bottom 24 of said air-duct 23, and said rim engages 90 the adjacent vertical wall of the ice-container 9, and acts as a guide, in placing or removing the said ice-pan 12.

The outer vertical walls of the said air-ducts 23 are formed by the adjacent vertical walls of the said ice-containers, and numerous openings or perforations 27 are formed in these walls at a point directly opposite said air-ducts, so that the warmer air and vapor from said show-case compartment 1 100 may pass out of the upper portion of the latter directly into said air-ducts, by way of said perforations 27, Fig. 5, and thence around the upper portion of said ice-containers 9, and make its exit through the perforations 25 in the said inclined bottom 24, into the ice-containers, in which it comes into contact with the cracked-ice and salt (or other refrigerating-materials) that are packed around the exterior of a plurality of 110 inclined tubes 28, as well as in direct contact with ice that is supported by and contained in the conical-pockets 29, which close the outer (and upper) ends of said tubes.

Said tubes 28 will hereinafter be referred to as the inclined air-cooling tubes.

The air, after being cooled by contact with the refrigerant in said ice-containers, makes its exit at a very low temperature, through a comparatively large drain-passage 30 in 120 the bottom of said ice-containers 9, as does also the water from the melted ice.

The drain-water from said drain-passage 30 of the ice-containers 9, drops directly into the open upper end of a vertical drain-spout 125 31 of a large drip-pan 32 that is supported on suitable legs or feet 33, at some distance below said ice-containers.

From said spout 31 of the drip-pan 32 the drain-water is conducted in a closed 130

drain-tube or pipe 34, which is connected to said spout, and passes flush with or below the floor 2, in a slightly inclined position, to the outer-chamber or shell 35 of a multiple-overflow drain-trap, which is located centrally of the floor of said show-case chamber or compartment 1.

Said outer-chamber or shell 35 of said trap is fitted with a removable-cover 36, for cleaning and repair purposes, and a plurality of overflow-chambers 37 of various heights, are located within said shell, in a well-known manner, so that the drain-water will rise in said outer-chamber to the level 15 of the highest wall of the highest inner overflow-chamber, thence overflow into the next highest overflow-chamber, and thence pass into the usual drain-pipe 38, that has a trap-cap 39 of ordinary construction.

20 A thimble 40, that is considerably larger than the said drain-passage 30 in the bottom of the ice-containers 9, directs the falling drain-water directly into the said drip-pan spout 31, and prevents the water from 25 splashing and spreading out in said drip-pan; while at the same time the cold air from the bottom of said ice-containers may pass freely therefrom, over the loose upper end of said thimble, into the bottom of the 30 refrigerating-compartments 6, and thence into the lower portion of said show-case compartment, in a much drier condition than if the drip or drain water were permitted to flow openly from said ice-containers 9, and 35 splash over and upon the said drip-pan 32.

Thus the much-desired cooled-air is provided in the show-case compartment 1, in a comparatively dry condition.

Said inclined air-cooling tubes 28, may be 40 of such size and number as is required to most efficiently cool the air, and their inner lowermost ends are soldered or otherwise secured to the vertical wall of their ice-container 9 that is next to the said show-case 45 compartments 1, with which said lowermost ends of said tubes are in free communication, through openings 41 cut in said ice-container walls. Fig. 4.

The upper ends of said air-tubes 28 are 50 cut off at an angle, to provide an inclined open filling-mouth 42 for entrance of cracked-ice and salt to the interior of the conical-pocket 29 of each tube, and said upper-most ends of said tubes are supported 55 by suitable brackets 43, which have vertical-arms secured to the adjacent vertical wall of the ice-container 9, and upon the horizontal-arms of which brackets the said ends of the tubes rest and are fastened by 60 means of solder or rivets.

The upper sides of said tubes 28 are preferably rounded, to facilitate the slipping of the ice from them, and also to drain off the water; but, as shown, the bottom walls of 65 said tubes are straight and flat, in order to

provide an extended flat bottom along which the cooled-air more readily flows towards the open end of said tubes, after it has been cooled by contact with the rounded upper walls thereof.

I do not limit myself to the exact form of the parts herein shown, as it is obvious that skilled mechanics can readily make changes in the same, without departing from the spirit of my invention or the scope of my claims.

For instance, as previously stated, but a single refrigerating-compartment, at one end only of the show-case compartment, may be used.

The operation.

A suitable freezing-mixture of broken-ice and salt, or other suitable refrigerating-material, is placed or packed within the ice-containers or containers 9, and around the exterior of the said air-cooling tubes 28, and in their conical-pockets 29, until all of the latter, and all ice-space in said containers, is completely filled or packed with such refrigerating-material, up to and in contact with the underside of the lids 17 of said containers, as well as upon the top of said lids, within said ice-pans 12.

It will be clearly seen that the rear (or outer) ends of the said air-cooling tubes 28 are closed by their conical ice-pockets 29, which are located entirely within the ice-containers 9, so the only opening of said tubes to the show-case compartment 1 is at the forward (or inner) ends of the tubes.

The warmer air and vapor from the show-case compartment 1 passes to the top of the latter, and thence circulates in the air-spaces on all of the vertical sides of the ice-containers 9, and passes downward therein after being cooled, to the space below said ice-containers, and finally back into the lower portions of the show-case compartment.

At the same time, a portion of the warmer air from the top of said show-case compartment 1, enters the said openings or perforations 27, in the upper portion of said ice-containers, and passes into and through the said horizontal air-ducts or passages 23, and makes its exit downwardly through the said perforations 25 in the inclined-bottom 24 of said air-ducts, into the upper part of the said ice-containers, below said lids 17; and thence the air passes downwardly as it is cooled, through the ice in said ice-containers, into the inclined-mouths 42 of said conical ice-pockets 29, and into contact with the ice contained in the latter; and thence passes to the bottom of the said ice-containers, where it makes its exit by way of the said drain-opening 30, to the air-space below said bottom; and finally into the lower part of said show-case compartment, and so on, in a continuous circulation.

But the principal cooling-effect is produced by the large cooling-surfaces of the interior of said air-tubes 28 and exterior of their said conical ice-pockets 29, the warmer air of the show-case compartment 1 entering the upper-portion of the open ends of said tubes, through said openings 41; thence passing back in said tubes to their upper rear portions, into contact with the upper walls of said conical ice-pockets; thence downwardly in contact with the very cold walls of said pockets; and thence into contact with the flat lower walls of said tubes, and along the inclined surfaces thereof, back to said openings 41, where the increasingly-cooled air makes its return-entrance to said show-case compartment 1 by way of the lower portions of said openings 41, and so on, in a continuous circulation, as aforesaid.

Of course, it will be seen that the refrigerated-air in (or from) the lowermost tubes 28 will be the coldest, for the reason that it has been subjected to a plurality of cooling-surfaces which gradually increase in efficiency toward the bottom (or lowermost) ones of the series of tubes.

Such a method of refrigeration produces a very high efficiency and economy, while keeping the food or other products in said show-case compartment 1 thoroughly refrigerated and dry.

The comparative dryness of the air in the show-case compartment 1 results from the use of the covering at all times of the drain or drip-water, and preventing it from saturating the air after it leaves the said drain-passage 30 in the bottom of the ice-containers, which is efficiently accomplished by the said closed drain-pipe 34 and the said multiple-chamber drain-trap 35.

I claim:

1. A show-case refrigerator, comprising a show-case compartment; transparent panels for said compartment; a refrigerating compartment at the end of said show-case compartment; an ice-container in said refrigerating-compartment; tubes closed at their rear ends by conical ice-pockets and located in said ice-container in a substantially horizontal position inclined toward openings in the vertical walls of said ice-containers that are next adjacent said show-case compartment,

so that the lower open ends of said tubes are freely open to the interior of said show-case compartment; and drain-connections for said ice-container covered to keep the air dry.

2. A show-case refrigerator, comprising a show-case compartment having transparent panels; refrigerating-compartments at opposite ends of said show-case compartment; ice-containers located in each of said refrigerating-compartments, and removable upwardly therefrom by way of doors in the top of the latter; tubes located in a substantially horizontal position within said ice-containers, and having their forward ends in free communication with the said show-case compartment, said tubes being inclined downwardly toward their open ends and having their rear ends closed by conical ice-pockets within said ice-containers; whereby a circulation of air will take place within said tubes, and the air will be cooled therein, and be discharged at the lowermost portions of said forward ends of said tubes into said show-case compartment.

3. In a show-case refrigerator, the combination with the parts named in the above claim 2, of means for permitting the air from said show-case compartment to circulate also in the space at the rear of said ice-containers, and at the opposite sides thereof, in spaces between the vertical inner walls of said refrigerating-compartments and the vertical walls of said ice-containers.

4. The combination with the parts named in the above claim 1, of a horizontal air-duct at the top of said ice-containers; and means for permitting a circulation of air from the upper portion of said show-case compartment into and through said air-duct, and thence downwardly through the refrigerating-means within said ice-receptacles, and out at the bottom of the latter, and into the lower portion of said show-case compartment.

In testimony whereof, I have signed my name to this specification in presence of two subscribing witnesses.

FERDINAND D. MAGUOLO.

Witnesses:

JOHN R. LANIGAN,
CHARLES THUENER.
